ATTORNEY.

UNITED STATES PATENT OFFICE

GEORGE W. CLAUSING, OF CHICAGO, ILLINOIS

HOISTING CARRIER

Application filed April 3, 1925. Serial No. 20,377.

This invention relates to improvements in hoisting carriers for tram rail systems, and has for its purpose providing more flexible operation of such systems than is ordinarily provided. In the system a jib rail is provided and pivoted to the main track so that the jib may be rotated at an angle to the track in order to more conveniently reach objects which are to be handled. And in connection with the jib my improvement comprises a carrier having a lifting head which can be raised or lowered by suitable means and which can be rotated with reference to the jib, and which can be projected a very material distance beyond the end of the jib. The complete system thus forms a very flexible arrangement for handling goods where special conditions prevail. A particular object is to provide for more lifting room for the head than the ordinary track will allow, and this I provide for any position of the carrier on the track. Other objects of the invention will be apparent from a consideration of the accompanying drawings and the description thereof:

Of the drawings Fig. 1 is an elevation of the system; Fig. 2 is a reduced diagrammatic plan view of the system; Fig. 3 is an enlarged front elevation of the carrier of the system; and Fig. 4 is a side elevation of the carrier head in its lowered position.

Of the drawings the main track 10 of the system may be any suitable track which allows the carrier to be moved from one place to another, this track being stationary. Pivoted to the ends of this track, in any suitable or ordinary manner, are jibs 11 which may be used as a continuation of the main track and which may be rotated to any convenient angle with reference to the track. Guys 9 support the outer ends of the jibs. The hoisting carrier 12 is mounted upon the jib 11 by means of flanges 13 which form a track for the supporting wheels 14.

My improvement comprises a load frame 17 which is supported by the wheels 14 on the track 13 in the following manner: Depending from the wheels 14 are U-shaped hangers 15 which support the frame 16. Rotatably mounted in this frame is a king bolt 8 which passes through the frame 17. By this ar-

rangement the load frame 17 is free to rotate under the track 13 to any extent that may be desired. When properly adjusted the entire load frame can be rotated under the jib beam. Pivoted to the load frame 17 near one end thereof are head beams 18 upon the outer ends of which are mounted the sheaves 19. These sheaves are spaced apart farther than are the supporting rollers 14, and hence will straddle the track 13 on the beam 11 when desired. The sheaves 19 are for supporting the operating cables 20. The ends of these cables are fixed to a cross beam 21 and to this beam is fixed the elevating hook 22. The other ends of the cables are connected to a drum 23, and in any ordinary or suitable manner, and the cables may be operated by an electric motor 24 or any other suitable means, as may be desired.

The lifting head of the carrier, comprising the sheaves 19, may be supported in the elevated position in any suitable manner. For this purpose I prefer members 25 which are pivoted to the frame 17 by means of a rod 26. When these members are in the position indicated by Fig. 1 the head is supported in its elevated position. However, if it is desired to lower the head I provide arms 27 which are fixed to the rod 26, and, by means of cables 28, fixed to the outer ends of these arms, the members 25 may be rotated to the position indicated in Fig. 4 so as to allow the head to move downwardly to a point below the extension of the lower portion of the track 11. The beams 18 will then rest upon the members 25, but will be supported in the lower position. When it is desired to elevate the head, suitable means may be used for forcing it upwardly to the elevated position and the member 25 may then be rotated to a position for supporting it.

It is obvious that, with a load on the hook 22, there would be a tendency to tilt the carrier by forcing the head end downwardly if the load frame 17 were supported by the king bolt 8 alone, and there would be an undesirable stress on the mechanism. To offset this abnormal stress I extend the frame 17 rearwardly and mount on the rear end the risers 30 which support wheels 31. These wheels normally are positioned under the track 13

so as to hold down the rear end of the frame. Obviously when so arranged, no matter how great the load on the head, there will be no undesirable stress on the load frame or the king bolt as the stress on the bolt will be a normal downward pull. In order that the load frame may be held in the proper position for bringing the rollers 31 immediately under the track 13 suitable means may be provided such as a pin 32 which projects into a recess 33 in the beam 16 when the frame is properly positioned. A spring 34 holds the pin in place, but allows the pin to be pulled out from the recess when desired in order to rotate the frame horizontally. A cord 35 may be used to pull the pin out from the recess and to assist in replacing it.

It is sometimes desirable to reverse the carrier on the track. For instance, if it is desired to operate the carrier on the left hand end of the track 10 the jib 11 is aligned with the main track and the carrier is run over to the left hand jib. In doing this the head need not be lowered to clear the track, as it is straddled by the sheaves 19. The pin 32 may then be released from the recess the head lowered and the frame rotated through 160 degrees so as to project the head towards the left instead of towards the right. The pin 30 then enters the recess 35 and the frame will be held in suitable position so as to bring the rollers 31 under the left hand jib track 11.

When there is no load on the hook 22, the weight of the motor, drum, and other mechanism tends to tip the head upwardly, and strain the king bolt. To offset this I provide rollers 36, supported by a rod 37. These rollers are so positioned that they will pass immediately under the track 13 when the carrier is moved back on the jib. The rollers 36 thus eliminate any undesirable stress on the mechanism by holding down the head end of the carrier.

It will thus be seen that I have provided a tram rail system carrier of much flexibility as the head may be raised or lowered to suit conditions and may be rotated with the jib track or rotated horizontally independently of the jib track so as to extend in opposite directions. The carrier also may be projected a material distance beyond the end of the supporting track, or may be withdrawn to any position on the jib or the main track without lowering the head. Hence the hoist may be used with the head elevated much more than would be the case without the forwardly and upwardly projecting head; and it may be so used at any position on the tram rail system and with the head projecting in any direction. Means also are provided for preventing on the carrier undesirable stress which would otherwise result by the use of a rotary supported or a forwardly projecting carrier.

65 It is to be understood that ordinary suit-

able equipment is provided; for instance, a limit switch 40 may be provided which is operated by means of a lever 41, the lever being operated by the beam 21 when the elevated hook has been raised to its maximum operable position. Various means may be provided for conveniently operating the crane, but as these are not a part of my invention they have not been expressly described. Furthermore variations may be made in the various elements herein described by those skilled in the art without departing from the spirit of my invention as disclosed by the following claims.

I claim as my invention:

1. In a tram rail system, a main track, a jib pivoted to each end of said track, a track on each jib with one end of each registering with the main track, a hoist carrier frame adapted to be supported by rollers on any one of said tracks or on either jib, a load frame comprising a horizontal beam normally parallel to and adjacent the track on which the carrier frame is supported, said beam being mounted for horizontal rotation on said hoist carrier frame, a head mounted for vertical movement on said load frame, and means for supporting said head above and below the plane of said main track, said head extending out beyond one end of said load frame so as to project beyond the ends of said jibs when said hoist is at its outermost positions on said jibs.

2. In a tram rail system a frame, a track mounted on said frame, wheels mounted on said track and a carrier frame supported by said wheels beneath said track, a load frame pivoted for horizontal rotation to said carrier frame, means for holding said load frame in line vertically with said carrier frame, a movable head mounted on one end of said load frame, and means for supporting said head above said track, and a roller mounted on the other end of said load frame immediately under said track.

3. In a tram rail system a frame, a track on said frame, wheels mounted on said track and a carrier frame supported by said wheels beneath said track, a load frame pivoted for horizontal rotation to said carrier frame, means for holding said load frame in line vertically with said carrier frame, a movable head mounted on one end of said load frame, means for supporting said head above said track, a roller mounted on the other end of said load frame immediately under said track, and a wheel mounted on said head and adapted to pass immediately under said track when the carrier is moved to its normal idle position.

4. In a tram rail system a frame, a track mounted on said frame, wheels mounted on said track and a carrier frame supported by said wheels beneath said track, a load frame pivoted for horizontal rotation to said car-

rier frame, means for holding said load frame in line vertically with said carrier frame, a movable head mounted on one end of said load frame, means for supporting said head above said track, a roller mounted on the other end of said load frame immediately under said track, a wheel mounted on said head and adapted to pass immediately under said track when the carrier is moved to its normal idle position, said head comprising beams and rollers spaced apart farther than the width of said track.

5. A tram rail system comprising a track, a hoist movably mounted on but depending from said tracks, a load head projecting upwardly from said hoist above said track, said head comprising two beams on opposite sides of said track, and cable guiding means mounted at the upper ends of said beams.

10. In a tram rail system, a track, a hoist load frame, means rolling on said track and pivotally supporting said load frame for horizontal rotation, said load frame extending parallel to said track and adjacent thereto during effective loading operations, means for locking said load frame in reversed positions extending parallel to said track, and thrust means between said track and said load frame for holding said load frame horizontally supported.

15. In a tram rail system, an overhead track, a hoist load frame suspended below said track, means movably mounted on but depending from said track and pivotally supporting said load frame thereon for horizontal rotation throughout 360° movement, said load frame extending parallel to said track, and thrust means between said track and said load frame for holding said load frame horizontally supported.

20. In a tram rail system, an overhead track, a hoist suspended below said track and comprising a roller frame below said track, a load frame comprising a horizontal beam extending parallel to said track when the hoist is in use and pivoted closely adjacent to and below said roller frame for complete rotation in a horizontal plane, an elevating head adjacent one end of said load frame, and means for normally supporting said elevating head so that it projects upwardly from the load frame with its upper end above the bottom of said track during effective use, and cable guiding means at the upper end of said elevating head.

25. In a tram rail system, an overhead track, a hoist frame movable along and suspended below said track for complete rotation in a horizontal plane, an elevating head on said hoist frame comprising a pair of beams one on each side of said track, cable guiding means at the upper ends of said beams, means for normally supporting said elevating head so that it projects upwardly 30 from the hoist frame with its upper end above

the bottom of said track during effective use, and means for lowering said elevating head to provide for rotation of the hoist frame.

30. In a tram rail system, an overhead track, a hoist suspended below said track and comprising a roller frame and a load frame pivoted thereto for complete rotation in a horizontal plane, an elevating head on said load frame, and means for normally supporting said elevating head so that it projects upwardly and outwardly from one end of the load frame with its upper end above the bottom of said track during effective use, cable guiding means at the upper end of said elevating head symmetrically arranged with the vertical plane of symmetry through the track, means holding said load frame parallel to said track, and thrust rollers on said load frame engaging the under surface of said track and provided on the opposite end of said load frame from said elevating head.

35. In testimony whereof, I hereunto set my hand.

GEORGE W. CLAUSING.
